(57) **CLAIM**

The ornamental design for a can with embossed pattern, as shown and described.

DESCRIPTION

FIG. 1 is a top perspective view of a can with embossed pattern according to our design;

FIG. 2 is a top plan view of the can with embossed pattern of FIG. 1;

FIG. 3 is a bottom plan view of the can with embossed pattern of FIG. 1;

FIG. 4 is front-side elevation view of the can with embossed pattern of FIG. 1;

FIG. 5 is a rear-side elevation view of the can with embossed pattern of FIG. 1;

FIG. 6 is a left-side elevation view of the can with embossed pattern of FIG. 1; and,

FIG. 7 is a right-side elevation view of the can with embossed pattern of FIG. 1.

The dashed broken lines shown are included for the purpose of illustrating portions of the can with embossed pattern that form no part of the claim. The dot-dash line illustrates a boundary of the claimed design.

1 Claim, 7 Drawing Sheets
